DESIGN FOR A DOMESTIC WASHING MACHINE

John T. Hume, Chicago, Ill., assignor to Electric
Household Utilities Corporation, Cicero, Ill., a
corporation of Illinois

Application June 26, 1936, Serial No. 63,519

Term of patent 14 years

To all whom it may concern:

Be it known that I, John T. Hume, a citizen of the United States, residing at Chicago, in the county of Cook and State of Illinois, have invented a new, original, and ornamental Design for a Domestic Washing Machine, of which the following is a specification, reference being had to the accompanying drawing, forming part thereof.

The drawing shows a domestic washing machine illustrating my new design.

Fig. 1 is a view in side elevation of the washing machine embodying my design; and

Fig. 2 is a plan view thereof.

I claim:

The ornamental design for a domestic washing machine, as shown.

JOHN T. HUME.
